HAIR SPRAY SHIELD

Onie N. Cass, 313 Emmett St., Palatka, Fla.

Filed July 8, 1965, Ser. No. 86,085

Term of patent 14 years

(Cl. D86—10)

FIG. 1

FIG. 2

FIG. 4

FIG. 1 is a rear perspective view of the hair spray shield showing my new design.

FIG. 2 is a front elevational view thereof;

FIG. 3 is a rear elevational view thereof; and

FIG. 4 is a bottom view thereof.

I claim:

The ornamental design for a hair spray shield, substantially as shown.
